(57) **CLAIM**

The ornamental design for the stackable wire telephone rack, as shown and described.

DESCRIPTION

FIG. 1 is a top plan view of a first embodiment of the stackable wire telephone rack of this invention;

FIG. 2 is a bottom view thereof;

FIG. 3 is a right side view;

FIG. 4 is a left side view;

FIG. 5 is a front view thereof;

FIG. 6 is a back view thereof;

FIG. 7 is a bottom view of a second embodiment of a modified stackable wire rack of this invention;

FIG. 8 is a top plan view thereof;

FIG. 9 is a right side view;

FIG. 10 is a left side view;

FIG. 11 is a front view thereof; and,

FIG. 12 is a back view thereof.
